UNITED STATES PATENT OFFICE.

DAVID PATON, OF HALIFAX, ENGLAND, ASSIGNOR TO JOSEPH WILD
& CO., OF NEW YORK, N. Y.

DESIGN FOR A CARPET-PATTERN.

Specification forming part of Design No. 5,894, dated June 4, 1872.

Specification describing a new and original Design for a Carpet, invented by DAVID PATON, of Halifax, in the county of York, England.

The accompanying photograph illustrates my invention.

This invention relates to a new carpet design, in which a large number of eight-leaved small rosettes, a smaller number of larger quatrefoils, containing split-ended crosses, and

a still smaller number of large square ornaments, decorated about the borders as shown, are employed.

I claim as my invention—

The design for a carpet, as shown.

DAVID PATON.
